UNITED STATES PATENT OFFICE.

WILLIAM J. TEMPLE, OF REDLANDS, CALIFORNIA.

COLLAPSIBLE BERTH FOR INFANTS.

972,732.

Specification of Letters Patent. Patented Oct. 11, 1910.

Application filed June 7, 1910. Serial No. 565,826.

To all whom it may concern:

Be it known that I, WILLIAM J. TEMPLE, a citizen of the United States, residing at Redlands, county of San Bernardino, State 5 of California, have invented new and useful Improvements in Collapsible Berths for Infants, of which the following is a specification.

This invention relates to a collapsible 10 berth for infants and it is especially useful to travelers to provide a temporary cot or cradle for an infant.

The object of the invention is to produce a device of this class which is simple of construction and which is constructed so that it 15 can be readily folded up and stored away when not in use.

In the drawing which forms a part of the annexed specification Figure 1 is a perspective illustrating the manner in which the device is used in practice. Fig. 2 is a side elevation of the device, certain parts being shown in cross section and broken away. Fig. 3, is an end elevation of the device, certain parts being broken away. Fig. 4, is an 20 end elevation of the device showing the body thereof in a folded condition ready to be stored away. Fig. 5, is a side elevation showing the frame which supports the device in a folded condition.

Referring more particularly to the parts, 6 represents the body of the device which comprises a bottom 7, having side boards 8 attached to the longitudinal edges thereof; 25 on these side boards 8, side leaves 9 are attached by hinges 10 which are arranged so that the leaves may be folded inwardly and downwardly upon the bottom 7 as indicated in Fig. 4. On the end edges of the bottom 7, 40 end leaves 11 and 11^a, are attached by means of hinges 12 adapting the end leaves to be folded inwardly over the bottom 7 as indicated in Fig. 4. The end leaf 11 is of the same height as the side leaves 9 and constitutes the head board for the bedstead or crib 45 which the device forms. On the outer sides of the side leaves and end leaves, clips or saddles 13 are provided and these saddles are in the form of plates having flanges 14 50 projecting outwardly on the upper edges thereof. On the inner sides of the side leaves 9 and the head leaf 11 horizontal cleats 15 are attached, said cleats being in the form of flat metal which is resilient. 55 These cleats are held in place by pins 16

which pass through slots 17 formed longitudinally in the cleats. These slots permit a certain amount of play in the cleats so as to permit them to be shoved away from the leaves to permit the edges of the bed clothing to be inserted in such a way that the cleats will hold the bed clothing in place. The bed which is formed in this manner is supported on a removable hanger frame 18, which frame comprises an outer bar 19 60 formed of two sections which are connected together by a hinge joint 20 at the middle point. To the ends of the side bar 19 end bars 21 are attached by hinge connections 22. The bar 19 is adapted to be received under flanges 14 of the clips 13 of the side leaves as shown, and the end bars 21 are adapted to engage in a similar manner with the clips on the end leaves. At the inner ends of the end bars 21 short arms 23 are attached by hinge connections 24, and they extend toward each other adjacent the side leaf 9 which is opposite to the bar 19. On the ends of the arms 23 hangers 25 are attached on pivot pins 26 and these hangers 75 extend up with their ends curved to form hooks to engage the back 27 of the car seat 28 as indicated in Fig. 1 or hung on a similar support. On the bottom 7 a suitable mattress may be placed and a bed for the infant 80 may be made upon this mattress in the usual manner.

When the device is set up as illustrated it forms a convenient cot for an infant. When desired the cot can be taken down and folded up so the parts will assume the relation shown in Figs. 4 and 5. In folding the cot as suggested the hanger frame 18 is removed from the body 6 and is folded up, the end bars 21 being folded on the hinge joints 22 90 so as to lie flat against the sides of the sections of the bar 19, and the arms 23 are similarly folded on their hinges; hooks 25 are folded in alignment with the arms as shown. The bar 19 is folded on its hinge 20 so that 95 the hanger frame will be folded into compact form. As indicated in Fig. 4 in folding the body 6 of the cot the side and end leaves are folded inwardly so as to lie upon the bottom. It should be understood that 100 the hanger frame not only forms a support for the body of the cot but its bars hold the side and end leaves in a vertical position.

What I claim is:

1. An infant's cot having a body having 110

2

side leaves adapted to fold thereupon, a folding hanger frame detachably engaging said body and adapted to support the same.

2. An infant's cot having a body with a bottom to support the mattress, leaves connected to the edges of said body and adapted to fold thereupon, a folding frame adapted to extend around the outer sides of said leaves and normally holding said leaves in an upright position, and means for supporting said hanger frame.

3. An infant's cot having a body with side leaves hinged thereto at the lower edges and adapted to fold inwardly thereupon, and normally disposed in an upright position about said bottom, a removable hanger frame having bars engaging and extending around said leaves, said leaves having means for engaging said bars to support said leaves thereupon, and folding hooked extensions on said frame for supporting the same.

4. An infant's cot having a body with a bottom to support the mattress, leaves hav-

ing hinge connections at the edges of said body and adapted to fold thereupon, a folding frame adapted to extend around the outer sides of said leaves, and means for supporting said hanger frame.

5. An infant's cot having a bottom adapted to support a mattress, having side boards extending upwardly therefrom, a hanger frame formed with bars extending along the outer sides of said side boards, means for supporting said side boards on said bars, said bars having a joint connection therebetween, enabling said frame to be folded up, and means carried by said frame for supporting the same.

In witness that I claim the foregoing I have hereunto subscribed my name this 1st day of June, 1910.

WM. J. TEMPLE.
